COINCIDENTAL LOCK

Filed Sept. 17, 1927

UNITED STATES PATENT OFFICE

WILLIAM J. DAVIDSON, OF DETROIT, AND LLOYD BLACKMORE, OF HIGHLAND PARK, MICHIGAN, ASSIGNORS TO GENERAL MOTORS CORPORATION, OF DETROIT, MICHIGAN, A CORPORATION OF DELAWARE

COINCIDENTAL LOCK

Application filed September 17, 1927. Serial No. 220,240.

The present invention relates to a combination ignition, lighting switch and transmission lock for an automotive vehicle.

It is an object of the present invention to provide a single lock operating means for a plurality of locks on an automotive vehicle. While a separate lock may be provided on any number of moving parts of an automobile, the confusion resulting from the use of several keys renders this objectionable. It is an object of the present invention to provide an ignition lock which can be connected with a locking means for any part of the vehicle to render that part inoperative. In the present case we have shown our ignition lock connected with the lighting switch and transmission lock, with modifications showing a connection with the intake riser and with the distributor shaft. However, the locking device we have disclosed below is not restricted to a combination with any particular lock but can be used with a lock on any vital part of the machine which is capable of being locked to render the machine incapable of operation.

It is an important feature of the invention to provide such a lock, operated by the ignition key, which permits of the operation of the ignition key at any time, regardless of whether the parts are in position to be locked and which will automatically come into operation when the parts move into a position in which they may be locked.

Other objects and advantages of the invention will appear in the course of the following description, taken in connection with the accompanying drawing.

In the drawing:

Figure 1 is a vertical longitudinal section of the improved locking device. Figure 1^a is a continuation of Figure 1, showing the connection of the locking means with the transmission.

Figure 2 is a transverse section taken on the line 2-2 of Figure 1^a, the parts being shown in locked position.

Figures 3 and 4 are sections on the line 3-3 of Figure 1, showing the parts unlocked in Figure 4 and locked in Figure 3.

Figure 5 is a modification showing the

lock connected with riser leading to the intake manifold.

Figure 6 illustrates another modification with the lock mounted in conjunction with the distributor.

Referring to the drawing, the numeral 10 indicates the cup-shaped lock casing which is mounted in the usual way on the dashboard. The numeral 14 indicates the usual face or cover plate fixed to the lock casing. In the upper part of the casing is the lighting switch and in the lower part the locking mechanism and ignition switch.

The lighting switch comprises a cup-shaped case 16 fixed within the lock casing. In the rear part of this case are the terminals 20 of the lighting wires. On the cover plate is the usual switch 22 provided at its rear end with a contact plate 24 adapted to establish contact with the terminals 20. The switch just described is of the usual construction, the only variation being that it is provided on the face of the contact plate 24 with arc shaped locking lugs 26. Two of these lugs 26 are provided, slightly spaced from each other to permit the pin 40, described below, to pass therebetween.

The lock is of the ordinary barrel type and comprises the outer non-rotatable cylindrical shell 28, fixed to the cover plate 14, and the inner rotatable core 30 which extends rearward beyond the end of the shell. Extending longitudinally of the core is a key way for the key 32. In the lower part of the barrel 28 are the usual locking pins. Each locking pin comprises an upper part 34 and a lower part 36, the shell and core being bored radially for permitting a limited reciprocation of the two parts in unison. A coil spring 38 normally holds the two parts raised so that the lower part 36 extends within both the shell 28 and core 30 and prevents relative rotation. The parts are so arranged that when the key is inserted, the parts 34 and 36 are pushed down against the tension of the spring 38 just far enough that the juncture of the parts 34 and 36 coincides with the juncture of the shell 28 and core 30. Rotation of the core is thus permitted as well understood in locks of this type.

In the upper part of the lock are the pins 40 and 41. The pin 40 extends from the lower part of the switch case 16 to the lower part of the shell 28. Fixed to the pin 40 is a washer 42 and surrounding the pin 40 between the case 16 and washer 42 is a compressed coil spring 44. In the upper part of the pin 40 is a slot 46. In the position illustrated, the slot 46 registers with the arc-shaped locking lugs 26 and permits rotation of the switch 22. When the key is withdrawn the pin 40 moves downward a limited distance and its upper end extends between the locking lugs 26 and holds the switch locked in closed position. The small supplemental pin 41 extends between the pin 40 and the key 32.

Fixedly mounted on the rear end of the core 30 is the switch arm 48 adapted to establish contact between the terminals 50 in the ignition system. Loosely mounted on the core 30 and held thereon by the switch arm 48 is the lock operating arm 52. This arm is provided with an arcuate slot 53 into which there extends a suitably shaped finger 51 preferably formed integral with the switch arm 48. The slot 53 is larger than the finger 51 to allow for a lost motion connection between the two. When the finger reaches either end of the slot it will carry along or swing the arm 52 therewith. Mounted on the arm 52 is a spring pressed pawl 54 provided with an aperture adapted to fit over the end of a pin 56. The pin 56 is provided at its lower end with a head and is surrounded by a small coil spring 58 tending to move it downward. When the key is removed the pin 56 is moved downward by the coil spring 58 so that its outer end coincides with the surface of the shell 28. Between the pin 56 and the key is the supplemental pin 57.

The transmission illustrated in Figure 2 is of standard construction. At 60 are indicated the usual shifter rails adapted to be reciprocated to change gear. The parts are shown in neutral in Figure 2. In the casting 61 between the two rails 60 is a T-shaped slot 62 in which a plunger 64 is adapted to slide. The rails 60 are provided with opposed grooves in which balls 66 are adapted to fit. A flexible steel wire 68 is connected at the outer end to the plunger 64 and extends up to and is connected with the end of the arm 52. The wire 68 extends down through the casing 10 and is surrounded, between the casing 10 and the casting 61, by a flexible tube 69. Within the casting 61 and surrounding the wire 68 is a compressed coil spring 70 tending to force the plunger between the two balls. When the plunger is withdrawn. (to the left as viewed in Figure 2,) the balls 66 are free to move toward each other and permit the rails 60 to be moved longitudinally.

The operation of our device is as follows: With the parts in locked position, as shown

in Figures 2 and 3, the ignition and lighting switches are open and the transmission rails 60 are locked in neutral position. When the key 32 is inserted in the lock, as illustrated in Figure 1, the pin 40 is raised so that the lugs 26 register with the slot 46, the pin 56 is moved to raised position so that it extends through the barrel 28, and the pins 34 and 36 are moved downward so that rotation of the core within the shell is permitted. The function of the pins 41 and 57 is the same as that of the pins 34. When the key is turned, a part of a revolution the switch 48 establishes a connection between the terminals 50 in the ignition system and moves the arm 52 to the position illustrated in Figure 4. The movement of the arm 52 is transmitted through the wire 68 to withdraw the plunger 64 and the balls 66 may then roll freely crossways of the slot so that the transmission rails can be freely moved. During the counter clockwise movement of the arm 52 above mentioned the spring pressed pawl 54 moves around and snaps over the pin 56. With the parts in this position the key 32 may be turned back to disconnect the ignition terminals, the slot 53 in the arm 52 permitting the core to rotate back to the original position while the arm 54 continues to be held by the pin 56, as shown in Figure 4. Either switch may then be freely operated without affecting the transmission. The key may be withdrawn regardless of whether the lighting switch is closed or the gears are in neutral. Such withdrawal of the key permits all the locking pins 34 and 36 to spring into their inner position to lock the core 30 and the pins 56 and 57 to move inward to release the pawl 54 so that it may be pulled around by the wire 68 at any time the rails 60 are moved to neutral position. After the key is withdrawn, if the switch 22 is moved to "off" position, the spring 44 forces the pin 40 down and the lighting switch is locked; likewise when the shifter rails are moved to neutral position the spring 70 forces the plunger in between the balls 66 and forces the balls into their respective slots in the rails, thus locking the transmission. The locking plunger and ball arrangement shown in Figure 2 may be connected at either end of the rails 60 or to the slotted gear shift castings 61, or at any other suitable place in the gear shift mechanism, depending on its specific construction.

Our invention is capable of being used in many connections and the various parts may be encased or "armoured" as desired. The light switch may be locked or unlocked by the insertion alone of the key and this is true whether the key operates the ignition switch alone, the transmission lock alone, or what not. The combination of locks is of much utility in conjunction with the one locking key and in this connection it must be understood the wire 68 though shown and de-

scribed as connected to a pin for locking the shifter-rails may be used for locking or moving any distant part such as a valve in the intake manifold or a switch or part of the distributor for controlling the engine operation.

In Figure 5 we have illustrated the flexible wire 68 connected with an arm 80 mounted on the pivoted damper 82 within the riser leading to the intake manifold. The flexible tube 69 surrounding the wire is connected with an opening in the side of the riser and within this opening and surrounding the wire 68 in position to exert force to close the damper 15 is the coil spring 84. The coil spring normally holds the damper closed so that air cannot pass from the carburetor to the intake manifold. When the key is turned the wire moves the arm 80 to the left, as illustrated, and the 20 damper 82 is moved to the dotted line position to permit the passage of air through the riser.

In Figure 6 there is illustrated the flexible wire 68 connected with a bell crank lever 90 pivoted at 92 in the support for the distributor. The lower arm 94 of the bell crank is bifurcated and extends into the channel of the annular member 96 fixed to the driving shaft 98. The shaft 98 is provided with a 30 single lug adapted to fit in a slot on the enlarged lower part of the shaft 100 extending down from the distributor head. The shaft 100 is permitted limited vertical movement. The usual coil spring 104 surrounds the wire 68 in the casing below the distributor and tends to rotate the bell crank lever clockwise, as illustrated to hold the parts disconnected. When the key is turned to rotate the bell 40 crank lever counter-clockwise, the slotted upper end of the shaft 98 is moved upward, and with it the shaft 100. When the lug 97 fits into the slot 99, the driving connection between shafts 98 and 100 is established.

We claim:

1. In a coincidental lock for automotive vehicles, a manually operable ignition switch and a means for locking a movable part of the vehicle, a member projecting from said lock to rigidly hold said switch from manual operation, and means on said lock having a lost motion connection for controlling said movable part.

2. In a coincidental lock for automotive vehicles, an electric switch and a means for locking a movable part of the vehicle, a locking barrel, a pin projecting away from said barrel and having a slotted end adapted to lock said switch, means on said switch to engage said pin during the locking and to conform to said slot when unlocked, and means on said lock having a lost motion connection for locking said movable part.

3. In a coincidental lock for automotive vehicles, a manually operable ignition switch and a movable part of the vehicle adapted to

be locked by said lock, means controlled by said lock for locking said switch, an arm on said lock, and means operatively connected to said arm for locking said movable part.

4. In a coincidental lock for automotive vehicles, an electric switch and a movable part of the vehicle controlled by said lock, a pin having a slotted end operated from said lock, means on said switch to engage in said slot or adapted to engage the pin to hold said switch in unlocked or locked position, an arm rigidly secured to the lock, a second arm operated through a lost motion connection by said first named arm, a second pin projecting from and operated by said lock, and means on said second arm adapted to engage said second pin when the lock is operated to hold the parts in locked relation.

5. The combination of claim 4, said last named means comprising a pawl.

6. The combination of claim 4, said last named means comprising a spring pressed pawl having an opening engaging over said second pin.

7. In a coincidental lock for automotive vehicles, a manually operable ignition switch and a means for locking a movable part of the vehicle, a pin projecting from and operated by said lock to rigidly hold said switch from manual operation and means on said lock having a lost motion connection for controlling said movable part.

8. In a coincidental lock for automotive vehicles, a manually operable ignition switch and a means for locking a movable part of the vehicle, a member projecting from said lock to rigidly hold said switch from manual operation, said switch having a projecting element and said member engaging said element to lock said switch, and means on said lock having a lost motion connection for controlling said movable part.

9. In a coincidental lock for automotive vehicles, a manually operable ignition switch and a means for locking a movable part of the vehicle, a slotted pin projecting from said lock to rigidly hold said switch from manual operation, a projecting element on said switch, the slotted portion of said pin conforming to said element when the parts are in unlocked position, and means on said lock having a lost motion connection for controlling said movable part.

10. In a coincidental lock for automotive vehicles, a manually operable ignition switch and a means for locking a movable part of the vehicle, a slotted pin projecting from said lock to rigidly hold said switch from manual operation, a projecting element on said switch, said element being out of the path of said slot when the parts are in locked position, and means on said lock having a lost motion connection for controlling said movable part.

11. In a coincidental lock for automotive

- vehicles, a manually operable ignition switch and a movable part of the vehicle adapted to be locked by said lock, means controlled by said lock for locking said switch, an arm on said lock, and means operatively connected to said arm for locking said movable part, said last named means including a second arm having a lost motion connection with said first mentioned arm.
- 5 12. In a coincidental lock for automotive vehicles, a manually operable ignition switch and a movable part of the vehicle adapted to be locked by said lock, means controlled by said lock for locking said switch, an arm on said lock, means operatively connected to said arm for locking said movable part, said last named means including an arm having a slot, and means on said first named arm engaging in said slot.
- 10 13. In a coincidental lock for automotive vehicles, a manually operable ignition switch and a movable part of the vehicle adapted to be locked by said lock, means controlled by said lock for locking said switch, an arm on said lock, means operatively connected to said arm for locking said movable part, said last named means including a freely mounted lock element operated by said arm, and means on said element to engage the lock to hold the parts in locked position.
- 15 14. In a coincidental lock for automotive vehicles, a manually operable ignition switch and a movable part of the vehicle adapted to be locked by said lock, means controlled by said lock for locking said switch, an arm on said lock, means operatively connected to said arm for locking said movable part, said last named means including a freely mounted lock element operated by said arm, a pin operated by the lock, and means on said element to engage said pin to hold the parts in locked relation.
- 20 15. In a coincidental lock for automotive vehicles, a manually operable ignition switch and a movable part of the vehicle adapted to be locked by said lock, means controlled by said lock for locking said switch, an arm on said lock, means operatively connected to said arm for locking said movable part, said last named means including an element freely mounted on said lock and operated by said arm, a pin projecting through the lock barrel and operated by the lock, and means on said element for engaging the pin to hold the parts in locked relation.
- 25 16. In a coincidental lock for automotive vehicles, a manually operable ignition switch and a movable part of the vehicle adapted to be locked by said lock, means controlled by said lock for locking said switch, an arm on said lock, means operatively connected to said arm for locking said movable part, said last named means including an element freely mounted on said lock and operated from said arm by means of a pin and slot connection,
- means operated by the lock and projecting therefrom, and means on said element adapted to engage over said lock operated means to hold the parts in locked relation.
